UNITED STATES PATENT OFFICE

BENJAMIN B. FELIX, OF CHICAGO, ILLINOIS, ASSIGNOR TO FEATHEREDGE RUBBER COMPANY, INC., A CORPORATION OF ILLINOIS

CHAIR CUSHION

Application filed December 14, 1926. Serial No. 154,684.

Chair cushions are now in general use made up of sponge rubber with one surface covered with fibrous material such as felt, woven fabric, real or imitation leather (all of which are intended to be embraced within the term "fabric" as hereafter used). Such cushions are sometimes criticized as being unpleasant in hot weather. This can be obviated by perforating the cushion, but if holes are punched in the combined materials, the edges are apt to be ragged and it is also difficult to apply a cover in which holes have been punched in exact registry with a rubber cushion in which holes have been formed.

In accordance with the present invention, the cushion is formed by molding the cover and body of the cushion together and curing the rubber in contact with the fabric. If a mold is used having pins in it to form the perforations in the final cushion and the cloth is perforated so that it will readily slip down over the pins, there will be a tendency for the sponge rubber to force its way between the pin and the edge of the cloth and rubber will show on the surface of the finished product. This objection can be overcome and a cushion of very attractive appearance can be made by forming holes in the fabric cover slightly smaller than the pins, then stretching the holes over the pins. Ordinarily it will be found more satisfactory to form the holes in the sheet of compound also but this is not always necessary. During the curing of the sponge rubber compound the pressure generated will force the fabric down over the pins, but the friction of the fabric against the pin will tend to keep the edge of the fabric adjacent each opening, from reaching the bottom of the mold, with the result that the fabric will be slightly turned in at the edge of each hole. The perforations in the fabric may be round or they may be formed in other ways, as for example, simply by making two crossing slits in the fabric, but in any event the holes should be made in such a way that when the cushion is finished a portion of the fabric covering will be turned into the hole.

The desired effect can be increased and an appearance given to the cushion that somewhat resembles tufting, if the pins are made

to taper all the way from their base to the top. By adjusting the amount of taper in relation to the size of the holes and nature of the fabric the extent to which the fabric will extend into the final opening can be modified to a very considerable extent.

In order to illustrate the manner in which a cushion of the type described can be produced, I attach hereto a drawing showing a cushion in the course of manufacture. The method of producing a cushion here described is such that the invention described and claimed in Hood & Wedlock Patent No. 1,610,286, dated December 14, 1926, will likewise be utilized.

In the drawings, Fig. 1 shows a sectional view through a portion of a mold with the materials that make up the cushion in place prior to the vulcanization; Fig. 2 is a sectional view through a fragment of a finished cushion embodying my invention; Fig. 3 is a sectional view of a modified form of mold.

For the purposes of illustration, the mold here illustrated is the one for producing the preferred form of cushion, that is, where tapering pins are used. It is to be understood, as has already been pointed out, that this is not essential to the broader phases of the invention.

The mold here shown has a lower part 2 with a cavity formed in its upper surface and has a flat upper part 3. Fixed in the lower part 2 are a series of pins 4 which in the present embodiment taper upward. In carrying out the manufacture of a chair cushion a sheet of stock properly compounded so that sponge rubber will result after curing is cut to a size and shape approximating the mold cavity in part 2 but slightly larger. One surface of this compound is then cleaned with a cleaning material such as kerosene and a piece of fabric is cut to approximately the same size and shape, laid over the rubber compound and pressed down to make it adhere smoothly to the compound. Holes are then punched through the compound and fabric in a position corresponding to the position of the pins 4 but the diameter of these holes is less than the diameter of the base of the pins 4. The sheet of rubber compound and the fabric is

then placed in the mold so that the tips of the pins pass through the holes which have been cut in the fabric and compound sheet. The edges of the compound sheet and fabric extend out of the mold. In the drawing the fabric is designated by the numeral 5 and the sheet of rubber stock is designated by the numeral 6. The mold is closed and heated to the vulcanizing temperature.

10 As the compound is heated it expands and the pressure forces the fabric down to the bottom of the mold between the pin 4. This pressure stretches the fabric slightly around the pins, turning the edge of the fabric up in close contact with the pins so that no rubber flows between the pin and the fabric to appear on the surface of the finished cushion. At the same time (depending in degree upon the taper given to the pin) the fabric immediately adjacent the base of the pin will be held away from the base of the mold so that the cushion will have a tufted appearance as is clearly illustrated in Fig. 2.

15

20

In Fig. 3 I show a modified form of mold. Here the lower mold 3' is formed with raised bosses 7 through which extend up the pins 4'. These pins may be mounted in a bottom plate 8 and may either be made so that they may be readily withdrawn to clean the mold etc. or may be made to fit permanently in place. In this modification the fabric 5' and compound 6' have formed in them holes slightly larger than the pins 4' but in this case the raised bosses 7 will function like enlarged bases for the pins and the pressure of the expanding compound will hold the edge portions of the fabric stretched and pressed against these bosses so that the resulting product will have portions of the fabric turned in about edge portions of the perforations and will have these edge portions of the fabric embedded in the rubber. Thus it does not vary the broad idea of this invention if the parts which form the perforations are pins alone or pins which combine with bosses formed in the bottom of the mold, both of which are embraced within the term "projections."

It is to be understood that the molds which are shown in the illustrations are given only as examples and that many variations may be made in the method of manufacture without departing from the spirit of the invention.

55 What I claim is:

1. As a new product, a cushion comprising sponge rubber with a fabric cover for the upper face integrally united to the rubber by vulcanization, said cushion having perforations extending through the rubber and the fabric and having edge portions of the fabric turned down around edge portions of the perforations and having the edges of the fabric embedded in the sponge rubber body.

60 65 2. A product as defined in claim 1, in

which the fabric around the perforations is stretched and held in stretched position by its adhesion to the rubber.

3. A product as defined in claim 1 in which the fabric is stretched between adjacent perforations to give a rounded cross sectional line between adjacent perforations, and the rubber body is likewise shaped accordingly.

4. A product as defined in claim 1 in which the perforations taper toward the lower side of the cushion and the surface of the fabric on any vertical section forms a smooth curved line continuation of the line of the side of each perforation.

5. The method of producing perforated cushions which comprises the steps of forming openings in a piece of fabric, putting such openings about upwardly extending projections in the mold, said openings and said projections being so related that the fabric between adjacent projections must be deflected and stretched to reach the lowest parts of the mold, putting a sheet of sponge rubber compound in the mold so that it is over the fabric, closing the mold and vulcanizing, whereby the expansion of the compound forces the fabric against the mold between the projections and leaves edge portions of the fabric turned about the perforations formed by said projections and embedded in the rubber.

6. A process as defined in claim 5 in which the projections are pins and the bottom of the mold between the pins is substantially flat.

7. A process as defined in claim 5, in which the projections are tapered pins and the openings are formed in the fabric of such a size that the edges of the fabric about the pins will be held a substantial distance from the bottom of the mold.

8. A process as defined in claim 5, in which the fabric and sheet of compound are put together and both perforated before being put in the mold.
